HER ATTORNEY.

UNITED STATES PATENT OFFICE.

EDITH M. PETERSON, OF OAKLAND, CALIFORNIA ASSIGNOR TO LAURA E. FISHER,
OF OAKLAND, CALIFORNIA.

DISPLAY DEVICE.

Application filed November 22, 1926. Serial No. 149,878.

The invention relates to a display device particularly adapted for use on milk bottles and the like.

An object of the invention is the production of an advertising or display device so formed that it can be applied to a milk bottle quickly and without the necessity of rearranging any of the parts.

Another object of the invention is the provision of a display device adapted to be optionally hung on the neck of a bottle, or made into an easel-supported display stand.

Other objects of the invention will be set forth in the following description of the preferred embodiment of the invention which is illustrated in the drawings forming part of the specification. It is understood that I do not limit myself to the showing made by the said description and drawings as I may adopt variations of my preferred embodiment within the scope of the invention as set forth in the claim.

Referring to the drawings:

Figure 1 is a plan view of the flat back comprising my display device as it appears before using. The heavy full lines indicate cuts and the dotted lines indicate creases or fold lines on which portions of the sheet may be folded.

Figure 2 is a perspective view, showing the display device applied to a milk bottle.

Figure 3 is a perspective view showing the back of my device when it is used as a display stand.

Broadly, my invention comprises a generally quadrilateral sheet of material, such as paper board, having a curved slit in one end to optionally form a hanger or an easel support. Alined creases are preferably provided adjacent the ends of the cut to facilitate the folding or portions of the sheet.

In detail, my invention comprises a generally quadrilateral sheet of fibrous material, preferably paper board, with a U-shaped slit 2 in one end thereof, the ends 3 and 4 of the slit being directed toward the opposite end of the sheet. The two legs of the U-shaped slit are substantially parallel with the lateral edges 5 and 6 of the sheet, and extending

outwardly from the ends 3 and 4 of the slit 50 to the adjacent lateral edge of the sheet are the alined creases 8 and 9. These creases provide a hinge which facilitates the movement of the hanger 7 formed by the partially severed portion lying outside of the U-shaped 55 slit. The width of the yoke-like portion of the hanger is determined by the size of the bottle or similar device on which it is to be placed. A large-necked bottle would of course require a wider hanger than a narrow-necked bottle. 60 The uncreased area 11 lying on the inside of the slit 2 remains coplanar with the body 12 of the sheet at all times and thus increases the surface available for advertising and display matter.

Frequently a creamery or milkman wishes to make some announcement to a customer but in the past has experienced considerable difficulty in doing so, as known methods were so troublesome and required so much time to apply that it became too costly. The device of my invention is intended to overcome this trouble by providing a display card having an integral hanger which is readily slipped over the neck of a bottle. Accidental displacement of my device is almost impossible, as the hanger fits well down on the neck of the bottle. By the use of my display device, announcements or other messages can be delivered with the milk and due to its position 70 on the bottle, cannot be overlooked by the customer.

My display device may be converted into an easel-supported stand for use in stores by folding the hanger or support 7 backwardly 85 until it rests against the body 12 of the sheet. Then by flexing the hanger outwardly, its opposite edges may be caught under the tongues 14 formed in the bottom of the body 12 of the sheet. In this manner, an easel support is provided which will maintain the device in an upright position. It is also my intention to have attractive representations and verses displayed on the device so that it may serve as a toy to amuse children after being 90 removed from the milk bottle.

I claim:
A display device comprising a sheet having

a U-shape slit in one end thereof, the ends of the slit directed toward the opposite end of the sheet, the portion of the sheet within the slit constituting a display area and the portion without the slit constituting a hanger with which the sheet may be suspended, and tongues formed in said opposite end of the

sheet and beneath which the edges of the hanger may be optionally caught to form an easel leg for the sheet. 10

In testimnoy whereof, I have hereunto set my hand.

EDITH M. PETERSON
